Pro. F. Rathbone, Albany, N. Y.,
Letters Patent No. 389, dated July, 8, 1851.

The Schedule referred to in these Letters Patent and making part of the same

To whom it may concern:

Be it known that I, John F. Rathbone of the City of Albany and State of New-York, have invented a new and original Ornamental Design for the Plates of a Cooking Stove and I hereby declare that the annexed drawings are full and accurate delineations of the said plates with their Ornamental Parts, which are combined to form the Stove: with the exception of the Back-Top and bottom plates, the side plate not represented being symmetrically similar to the one shewn, and the half of the front plates not represented being also symmetrically similar to the half shewn.

What I claim as my production and desire to secure by Letters Patent is the Combination and arrangement of Ornamental figures and forms represented in the accompanying drawings forming together the Ornamental designs for the plates of a Cooking Stove.
